UNITED STATES PATENT OFFICE

FLORENCE WARES, OF SEATTLE, WASHINGTON

FURNACE FRONT

Original application filed July 9, 1928, Serial No. 291,330. Divided and this application filed April 6, 1931. Serial No. 527,903.

The invention is a completely sealed enclosure at the front of a furnace which encloses the ends of the grates, shaker bars and ash pan and forms an auxiliary housing providing a double check to prevent ashes sifting out of the front of the furnace.

This application is a division from my prior copending application for a patent for a furnace grate which was filed July 9, 1928, with the Serial Number 291,330, the former being now restricted to the grate.

The object of the invention is to provide a furnace in which the lower part of the front is completely enclosed to prevent dust from the ashes dropping from the grate to the ash pan escaping.

Another object of the invention is to provide a furnace front having a narrow horizontal opening through which the grate bars may readily be removed.

A further object of the invention is to provide an auxiliary furnace front which may be used with any type of furnace.

And a still further object of the invention is to provide an auxiliary furnace front for enclosing the grate ends and ash pan which is of a simple and economical construction.

With these ends in view the invention embodies a housing adapted to be attached to the lower portion of a furnace front, a plate forming the lower part of the front with grate and ash pan openings therein, another plate forming a closure for the grate openings, and an upper and lower door in the housing with a damper in the lower door.

Other features and advantages of the invention will appear from the following description taken in connection with the drawings, wherein:

Figure 1 is a view showing the housing installed at the front of a furnace.

Figure 2 is a cross section through the housing looking toward the furnace with part broken away.

Figure 3 is a cross section through the housing and lower part of the furnace front taken at right angles to that shown in Figure 2.

Figure 4 is a view showing the grate opening closure plate.

In the drawings the furnace front is shown as it would be made wherein numeral 1 indicates the plate forming the furnace front, numeral 2 a housing forming an extension at the front of the furnace, and numeral 3 the 55 grate opening closure plate.

The upper portion of the front of the furnace is formed by a plate 1 which terminates at the point 4 and the lower portion is formed by a plate 5 which extends from the point 6 to the point 7 providing an opening 8 through which the grates may be removed and replaced, and also a lower opening 9 for the ash pan which is indicated by the numeral 10. The upper edge of the portion 5 is provided with two semicircular openings 11 and 12 in which the ends 13 of the grate bars rest as shown.

A plate 3 is provided to cover the opening 8 and this is held in a clip 14 on the plate 5. Openings 15 are provided in the lower edge of the plate 3 to fit over the ends 13 of the grates and smaller openings 16 are provided to fit over thumb screws 17 in the plate 5 and clip 14 which may be screwed inward to bind and hold the plate in place. It will be noted that this plate fits snugly over the ends of the grates and completely seals the opening 8 through which the grates pass. A knob 18 is provided at the upper edge of the plate by which it may be held when removing or replacing. The upper edge of the plate may be straight as shown in Figure 2 or bent over as shown in Figure 3 as may be desired.

The housing 2 is of a rectangular shape with an upper door 19 and a lower door 20 at the front and both of the doors are hinged to the housing at the point 21 and arranged in such a manner that when open the entire 90 front of the housing will be open to permit the grate bars and ash pan to be removed and replaced therethrough. Both doors are provided with knobs 22 and the lower door has an opening 23 which is covered by a 95 smaller door 24 and the door 24 has a damper 25. The door 24 is pivotally mounted on a horizontal pin 26 which is supported in bearings 27 at the upper edge of the door 20 and it will be noted that it will normally hang 100

straight downwardly by gravity to close the opening 23. This door may be mounted or attached in any other suitable manner.

It will be understood that any other suitable changes may be made in the construction without departing from the spirit of the invention. One of which changes may be in the design, construction, or arrangement of the housing, another may be in the use of other means for sealing the openings at the ends of the grate bars, and still another may be in the use of doors of a different type or design at the front of the housing.

The construction will be readily understood from the foregoing description. In use the front of the furnace and the housing may be provided and installed as shown and it will be observed that when it is desired to shake the grate or remove the clinkers therefrom it is only necessary to open the upper door and when it is desired to remove the ash pan it is only necessary to open the lower door. This device provides a double check on the ashes sifting through and out into the room as the furnace front 1 is practically sealed so that very few ashes will sift through into the compartment 2, and as there are very few ashes in this compartment there will not be much chance of them escaping out into the room. At the same time this construction makes it possible to readily remove and replace the grate bars without tearing down or injuring any part of the furnace.

Having thus fully described the invention what I claim as new and desire to secure by Letters Patent, is:

1. In a furnace front of the type having a flat plate forming the front of the furnace with grates having shaker ends extending through the plate and an ash pan under the grate, said front plate having horizontal openings providing passage for the said grates and ash pan, a readily removable plate forming a closure for the grate opening, said plate having slots fitting over the grate ends, clamping members for holding said plate, a complete housing enclosing the lower portion of said furnace front and covering said grate and ash pan openings, doors at the outer end of said housing making it possible to open the entire area thereof, a smaller door hinged on one of the said housing doors and covering an opening therein, and a damper in said smaller door.

2. In a furnace of the type having shaker grates and an ash pan, a plate forming the furnace front having horizontal openings for the grate bars and ash pan, a closure for the said grate bar opening, a box like housing enclosing the lower portion of said furnace front, doors at the outer end of said housing, and a damper in one of the said doors.

3. In a furnace front for a furnace of the type having grate bars with an ash pan below the grate, a plate forming the furnace

front having horizontal openings providing passage for the grate bars and ash pan, a removable plate forming a closure for said grate bar opening, means for holding said removable plate, a box like housing forming an enclosure for the lower part of said furnace front and covering said grate and ash pan openings, doors at the outer end of said enclosure, a smaller door covering an opening in one of said enclosure doors, and a damper in said smaller door.

In testimony whereof I affix my signature.

FLORENCE WARES.
